UNITED STATES PATENT OFFICE.

WILL K. MONROE, OF CLEVELAND, OHIO, ASSIGNOR TO THE BROWN HOISTING MACHINERY COMPANY, OF CLEVELAND, OHIO.

MEANS FOR CLAMPING CARS IN TIPPLES.

1,126,550.

Specification of Letters Patent. Patented Jan. 26, 1915.

Application filed March 21, 1914. Serial No. 326,189.

To all whom it may concern:

Be it known that I, WILL K. MONROE, a citizen of the United States, residing at the city of Cleveland, in the county of Cuyahoga and State of Ohio, have invented a new and useful Means for Clamping Cars in Tipple, of which a clear and exact description, with references therein to drawings that accompany and make a part of the 10 specification, is hereinafter fully set forth.

The invention belongs more especially to the class of mechanical instruments for the unloading of gondola or open-top railway cars of their gross cargoes such as ore, coal, limestone and similar bulky or granular material, by first raising the car, within a tower-like structure, to a predetermined point, and then overturning the car before and along the mouth of a chute that leads to 20 a vessel or other receptacle below. By reversing the raising process, the emptied car is lowered to the base of the tower, when it is moved therefrom outwardly on tracks provided for the purpose, and another car 25 brought in for a like unloading.

An important feature of apparatus of this class is the efficient locking or clamping of the car upon the cradle or platform by which it is carried up and down through the 30 tower during the unloading movements, and the invention now about to be set forth has to do with this feature alone of the appliances referred to.

In the accompanying drawings Figure 1 is a tipple provided with the clamping means in question. Fig. 2 is an end elevation of a cradle with the clamping-bar employed at the lower limit of its travel relative to the car to be clamped. Fig. 3 shows the relative position of two members of a series of clamping-bars when one of said members is in its initial engagement with a car, and the other is idle. Fig. 4 shows the relative position of the same members during the remainder of the dumping movement. Fig. 5 shows the relative positions of the cradle, car and clamping-bars last referred to, at the moment of dumping. Fig. 6 is a half-plan view of the cradle and clamping-bars shown in Fig. 4. Fig. 7 is an enlarged detail of the inner end connections of said bars. Fig. 8 is a plan view of Fig. 7. Fig. 9 is a side elevation of the means provided for stopping or limiting the relative movement of the cradle and the upright 40 standards passing therethrough to which said inner ends of the clamping-bars are connected, as shown; also the anchorages of clamping-ropes employed. Fig. 10 is an end elevation of Fig. 9. Fig. 11 is a vertical cross sectional view of the outer and inner ends of a clamping-bar and, Fig. 12 is a vertical cross-sectional view through the middle portion of such a bar. Figs. 13 and 14, and Figs. 15 and 16, severally illustrate variant details of the invention.

In said figures 1 represents a frame-work tower-structure, and 2 the usual L shaped cradle to receive and carry the car to be unloaded. 3 indicates said car throughout the drawings. A detailed description of the tower structure in which said cradle operates, the means employed for raising and lowering said cradle and overturning the same with its loaded car and other usual features, are probably unnecessary in this specification, as such features are only incidental to the invention involved, are variable in their nature, and are sufficiently indicated in the drawings for an understanding of the same by those versed in the art. The invention, however, does depend upon and pertain to that method of confining a car upon the cradle which is directly effected, not by positive and distinct clamping members in the ordinary significance of that phrase, but by a series of counterweighted chains or ropes so arranged that when the car is overturned, at its uplifted point, by the tilting of the cradle, the upper edges of the car-body will contact with and come into bearing against said chains, and the car thereby be embraced by said chains and firmly secured in its place relative to the cradle. In employing this method of fastening the car in place during the overturning movement, it has been found necessary, in order to meet and prevent injurious crushing strains, by the chains against the car body, to interpose rigid cross-bars between opposite contact points of the car's edges and the embracing chain, and, the use of such bars and parts indirectly for this purpose, is now familiar in the art. In all prior uses of the sort, so far as I am aware, the rigid parts or bars employed have also been given the apparent or real function of clamps proper, and been denominated accordingly, although, in strictness, their office, in some cases, is for the most part 100 105 110

merely negative and passive, and simply to guard and serve as barriers against any untoward results of the clamping. Such clamping, in fact, is chiefly effected by the 5 chains themselves.

The improvements I introduce are concerned solely with the providing of clamping-bars, of the class referred to, that have the more limited functions last referred to, 10 and whose chief merit is in the mode of their connection and operation with respect to the other parts and entireties involved. The improvement, accordingly, comprises essentially an arrangement, for each of said 15 chains employed in a given car-dumper, of pivoted bars 4, or 4^a, with bearing surfaces 5 and 6 at each end respectively, with which the upper edges of the sides of the car will become engaged when the car is uplifted 20 by the cradle, and, with the upper surface of which bars, said chains or ropes employed will severally come into engagement as the car is clamped. As shown in the drawings, said bar-arrangement, in each case, is made 25 up of the normally horizontal bars 4 (or 4^a), having flat surfaces 5 and 6, on the under side of the ends of the bars in the same plane, one with the other, and a corresponding series of poles or standards 7, 7, to 30 which said bars are severally jointed at their inner ends in a manner to be more particularly described.

A material element in car-dumpers or tipples of the kind under consideration is 35 the platform, commonly known as the cradle, on to which the car is brought for raising and overturning. This platform is usually right-angled in cross-vertical section, being composed of a horizontal platform member, of the requisite dimensions to 40 admit a car thereon, and an upright or vertical member, of similar proportions, along one side of the same. The structure is, accordingly, generally made up, as a frame 45 work whose main components are a series of, say, four equi-spaced L shaped ribs or knees 8. For the purposes of the device in question, oppositely related vertical guides 9 are arranged in pairs on the 50 inner face of said upright cradle-member. Between the members of these pairs the clamping-ropes 10, pass freely downward to fixed anchorages 11, 11, on the tower-structure cradle, or elsewhere below. Said 55 guides are grooved or recessed on their inner opposite faces throughout their length, to receive, at a slide fit, corresponding flange-like longitudinal projections or tongues 13, on either side of the standards 60 7, at the inner edges of their sides. By making the portions 14 of the standards 7 thus slidably connected to the cradle, box-shaped, as shown in the drawings (Fig. 8) ample room, behind the pivotal connection 65 between the standards 7 and the cradle 2,

for said clamping-ropes and other details to be described, will be provided for. In order to effect said connection, a pair of parallelly arranged bracket-like projections 16, having eyes 17 to receive the connecting pin or pivot 70 18, are located at the front of said standards near their tops. A corresponding hole or eye is located near the inner ends of the bars 4, and the latter are thereby fulcrumed upon the pins 18 between the brackets 16 and the 75 sides of the shafts or standards 7 which latter, at their upper ends, are left open and unobstructed for the purpose. The inner ends of the bars 4 are curved downwardly in the form of sheaves whose centers severally coincide with the pivot or fulcrum 18. The bars, themselves, are shown as double-scored along their entire top and ends to guide the several clamping-ropes 10 with which they are to contact, Figs. 11, 12. 80 85

The upright standards 7 are represented in the drawings as made up of two sections or portions, the upper portion 14, containing said box-shaped sections, and the lower portion 15, which is pole-shaped. Said sections are connected one to the other by bolt 19, and, as will appear, with the upper portion 14 slightly overhanging the lower portion 15 on the cradle side. (Figs. 9 and 10). The standards 7, thus formed, extend downwardly through the cradle 2. They are of suitable length to have the jointed part of their upper ends project well above a car, when the car rests on the cradle, and the latter, and said standards, are in their normal positions. In such position the standards themselves rest upon and are supported at their lower ends by fixed exterior supports 20, which are provided for the purpose at the base of the tower. 95 100 105

In order to actuate the bars, around their fulcrum points with respect to the upright standards with which they are connected, and thereby to elevate the bars against or out of interference with the cars when the 110 same are brought in upon the cradle for unloading, the invention provides links 21 and 21^a, respectively connected, at their upper ends, to the opposite sides or faces of said bars at points thereon between said 115 fulcrum and said cradle, and, at their lower ends, firmly joined together by the pins 22. These pins extend through and project from the outer face of said links, in each case, so that their projecting ends may enter 120 and be movable between the upright parallel guides 23 and 23^a that are located, for the purpose, on the inner sides of the box-shaped portion of the standards 7, before explained. The length or degree of the actual movement of said ends and the links to which they pertain, is determined, of course, by the extent of the desired movement of the bars around their fulcrums and the relative location, with respect to said 125 130

fulcrums, of the point of attachment of the links to the bars. The difference in length between the lever-arms involved is great enough, in any case, to insure that such link-movement will be a comparatively limited one. In the arrangement illustrated in Fig. 7, for instance, the calculated movement of the links, in order to elevate the outer arm of the bars to the angular position denoted by the broken dotted lines of the same, will be no greater than the distance between the dotted lines to which the opposite arrows, in the figure, respectively, point and pertain. It is evident that when sufficient force is applied to this stirrup-like arrangement of the links 21 and 21^a, to carry the same downwardly, the lever-arms, which, together constitute said bars, will be correspondingly actuated, and the longer of the two arms, or the clamping-bar proper in each case, will be elevated to the predetermined angle as the shorter arm is depressed and carried downwardly by said force. Also, that, when such force, having been so exerted, is at length relaxed and withdrawn, the weight of said longer-arm, or bar 4, under the conditions, will tend to carry said arm down, around its pivotal point, to its original position and place. The device in question, accordingly, utilizes the weight and necessary movement of said cradle, as it sinks to or rises from its normal place or position, for and as this very link-actuating force, and, to this end, provides firm hook-like horizontal projections 24 upon said cradle, intermediately of each pair of said links, and at a point on the cradle that is in alinement with and coincides with the position of the pins 22, when the cradle, and said pins and links are at the lowest, or normal limit of their travel. In this manner, when a car has been dumped and the cradle is descending with the same to its starting point at the foot of the tower, said hook is sure to encounter the cross-pins 22, as soon as the feet of the standards 7 meet and are stopped by the exterior support 20, and, by its superior weight to thereby carry the links downward through the short remainder of the descent, and thereby depress the shorter arms and correspondingly raise the longer arm of the clamping-bars off from the car and into positive positions above the same as shown in Fig. 1.

In order to check an undue descent of the bars through and below the cradle when not in bearing across the top of the car, and the cradle is moving upward in the tower, any suitable means may be employed for limiting the freedom of their movement in this respect. In the drawings such a means is shown in the stop 25 extending outwardly from the vertical member of the cradle, and to be carried into engagement with the lower

end of the inwardly overhanging box-shaped portion 14 of the standards 7. In order to counterpoise the weight of the longer arms of said bars when not in contact with a car, and prevent any undesirable lifting effect by them through the shorter arms of the same, and, also to definitely limit the downward radial movement of said arms around their fulcrums, I provide a rope and sheave system, as indicated, which is attached at one end to said clamping-bars by ropes 26, and, after passing up to and over suitable pulleys or sheaves terminates in a suspended counterweight 27. Further functions of said system are provided for by the stops 28 to the upward travel of the counterweight, and consequent downward movement of the arm to which said weight is opposed. Said system will also operate to moderate the force of the fail of said bars, around their pivots, when the hooks 24 are released from engagement with the pins 22 of said actuating links 21 and 21^a.

It will be found good practice to so fix the length of the rope, used in said system, in relation to the location of the stop 28, and other relevant conditions, that the outer or forward end of said clamping-bars when at said limit of their downward travel will have ample clearance for the cars to be clamped and will be lower than the inner end of bearing surfaces 5 of such bar, all as indicated in Fig. 2.

It has been explained how, by and upon the descent of the cradle for a new car, the clamping bars, by reason of the arrangement covered by the invention, automatically break their contact with the empty car and assume the proper position for handling the next, or loaded car. Such position, in relation to the entire apparatus, is illustrated in Fig. 1, and, as to the various details involved, by others of the figures.

As the cradle starts upward with the loaded car, the pins 22, and their link connections, are, at once, relieved from the weight of the cradle exerted through the hook 24, and the outer lever-arms of all the clamping-bars are thereupon free to fall by their own weight through the predetermined distance permitted by their counterweight systems into the horizontal positions shown in Fig. 2. At that same instant the cradle will bring the car up into engagement with the bearing surfaces 5 and 6, and, thereafter, and in this relation of the several parts will continue to hoist to the point of overturning. As soon as this latter movement begins, the clamping-ropes 10 under the tension of their counterweights will rapidly be engaged by the clamping-bars 4, sequentially within their scores, around their inner sheave-ends to and down their outer extremities, which process will, 120 125 130

in consequence, firmly compress said bearing surfaces 5 and 6 against the top edges of the car's sides and completely clamp the car itself against any irregular movement or escape from its destined place.

It is evident that various changes or modifications of the general idea and arrangements I have herein presented, may be made without departing from the scope of the invention as I intend to claim the same, and I do not wish to limit myself to the precise manner of embodying the invention as depicted in the drawings; such variations, for instance, would include other lever or clamping-bar actuating connections than links, indeed, an arrangement instead of links, that is more in the nature of a mere integral prolongation of the inner end or short lever arm of the bars, and with which an engagement with the cradle is to be effected, and, such engagement itself, may be conceived as possible, and within my claims, although the positive engaging parts are on the lever-actuating members instead of on the cradle, or are on, or project directly from said inner end for the purpose. Such variations are disclosed in Figs. 13 to 16, where, in Figs. 13 and 14, instead of the links 21 and 21^a, movably connected at one end to the standards 7, and, at the other, to the inner or shorter end of the fulcrumed bars 4, and the projections 24 to engage with and actuate the same, I substitute, as a lever-actuating arrangement in the connection, radial or hanger-bars 29, 29, pivoted, at one end, to lugs 30, on the inner side of the upright member of the L-shaped cradle, at points thereon above the fulcrum points 18, when the cradle 2, and standard 7 are in their normal static places, and at each side, respectively, of the inner or lever-arms of the bars 4. Said hanger-bars 29, are forked at the other or lower ends, to embrace trunnion-like projections 31 on said lever-arms, when brought into contact with the same by the descent of the cradle, and thereby to carry said lever-arms downwardly to a predetermined degree.

A further arrangement is disclosed in Figs. 15 and 16, wherein the lugs 30 carry a cross-pin 32, to engage a keel-like part 33, on the under side of said lever-bars, and similarly actuate said arms downwardly around the fulcrum 18.

A simpler, and in some respects, preferable embodiment of the invention, is illustrable, by the dotted lines in several of the figures, by conceiving that the lengths of the sustaining ropes 26, are such that they will stop or limit the descent of the outer ends of the bars 4 at a predetermined point above the cars so that, when all parts are in their normal positions relatively, the

bars, themselves, will point diagonally upward, as indicated by the dotted outlines of such a bar, marked "Normal", in Fig. 3. Such limitation may be fixed either by permanently fastening the sustaining ropes 26, of the requisite length for the purpose, at the point 28, or, the rope being of the full length indicated in Fig. 2, by transferring the stop 28, shown in full lines in the figure, to and permanently locating the same immediately above the normal place for the counterweight 27 therein. In this form of the invention any direct lever-actuating means are not required since the limited length of rope at one end of the bars, and the standards at the other end will, together, hold the bars at a sufficient height to afford the necessary clearance for the cars as they enter the cradle, and the need of said lever-bars themselves, will disappear in consequence.

In actual operation, as the loaded car and its supporting cradle, in this form of the device, move upward through the tipple, the inner edges of the car body will first encounter the inner end of said bars near the fulcrum point and carry the bars vertically upward at said inner end, until the outer edges of the car meet the forward ends of the bars and a full engagement with said bars occurs. The means of suspending the outer end being of a nature to leave the bars free for the purpose, the car can now be carried upward in said engagement, through all the ensuing tippling movements. Of course, the relative heights of the opposing ends of the clamping bars, when the latter, in this form of the invention, are in their normal place, may be reversed, if desired, by varying, to the requisite degree, the relative dimensions of the sustaining members of the respective ends.

Having thus fully described my invention, what I claim as new and wish to secure by Letters-Patent is:

1. In a car-tipple having a cradle for elevating and lowering the cars therethrough with a vertical member at one side of the same, the combination of sheaves at the upper part of the tipple, clamping ropes anchored at their ends to said cradle and passing upwardly along said member to and around said sheaves, counterweights connected to the free ends of said ropes, a series of upright standards slidably connected to the vertical member, in front of said ropes, and freely extending through said cradle below; fixed supports for and in alignment with said standards, beneath the cradle; a series of clamping-bars fulcrumed near their ends to the standards, and extending cross-wise of the cradle therefrom; lever-actuating members connected to the inner ends of said bars, and means on said

cradle for engaging the lastnamed members at a predetermined part of the cradle's travel, substantially as shown and described.

2. The combination, in a car-tipple, of a vertically moving L-shaped cradle, sheaves on the upper part of the tipple, clamping ropes anchored to said cradle at their ends and extending upwardly along the upright member of the same to and around said sheaves; counterweights attached to the other, or unanchored, ends of said ropes; a series of upright standards movably connected to the upright members, in front of said ropes, and freely extending through the cradle below; fixed supports for and in alignment with said standards beneath the cradle; a series of clamping bars pivotally connected to the standards and extending cross-wise of the cradle; links connected to the inner ends of said bars, and means on the cradle for engaging said links at and during a predetermined part of the cradle's downward travel through the tipple, substantially as shown and described.

25 3. The combination, in a car-tipple, of a vertically moving L-shaped cradle, sheaves at the upper part of the tipple, clamping ropes anchored to said cradle at their ends and extending upwardly along the upright member of the same to and around said sheaves; counterweights attached to the other, or unanchored, ends of said ropes; a series of upright standards movably connected to said upright member in front of said ropes and freely extending through the cradle; fixed supports for and in alignment with said standards beneath said cradle; a series of clamping-bars pivotally connected to the standards and extending cross-wise of the cradle, together with suitable means, on said cradle and the inner ends of said bars, for becoming and being in engagement, one with the other, at and during a predetermined part of the cradle's downward travel 45 through the tipple, to thereby actuate said bars upwardly around their fulcrums, substantially as shown and described.

4. The combination, in a car-tipple having an L-shaped cradle therein and clamping ropes passing upwardly therethrough along the inner face of the vertical member of said cradle, of a series of upright standards on said face, in front of said ropes, adapted normally to pass through said cradle below;

fixed seats for and in alignment with said standards beneath the cradle; a series of clamping bars, for the top-edges of a car's body, fulcrumed, near their inner ends to the standards, together with suitable means for effecting an engagement between said inner ends and said cradle, at and during a predetermined part of the cradle's downward travel, comprising, essentially, bar-actuating projections on the cradle, above and in alignment with said inner ends when 65 said bars are in their clamping positions with respect to a car, and, at a point which will bring said projections into engagement with said ends when the cradle descends to, and said cradle and standards are at, their 70 normal places at the base of the structure, substantially as shown and described.

5. The combination in a car-tipple, of an L-shaped cradle; a series of upright standards slidably connected to the vertical member of the cradle and adapted normally to extend through said cradle below; fixed seats for and in line with the standards at the base of the tipple; a series of clamping-bars fulcrumed near their inner ends to said standards; sheaves on said tipple above the limit of travel therein of the cradle and in alignment with said standards; clamping ropes counterweighted at one end and extending over said sheaves and downwardly 85 to anchorages below the overturning point of the cradle and in the same planes, respectively, as said sheaves, clamping-bars and standards, together with suitable means for effecting an engagement between the inner 90 ends of said bars and the cradle, at and during a predetermined part of the cradle's downward travel, comprising, essentially, bar-actuating projections on the cradle, above and in alignment with said inner ends 95 when said bars are in their clamping positions with respect to a car, and, at a point which will bring said projections into engagement with said ends when the cradle descends to, and said cradle and standards 100 are at, their normal places at the base of the structure, substantially as shown and described.

WILL K. MONROE.

In presence of—
C. S. MALTBY,
L. P. LIPPS.
